UNITED STATES PATENT OFFICE

142,560

DESIGN FOR A TEXTILE FABRIC

Annette Honeywell, Los Angeles, Calif.

Application March 22, 1945, Serial No. 118,618

Term of patent 7 years

(Cl. D92—1)

To all whom it may concern:

Be it known that I, Annette Honeywell, a citizen of the United States, residing in Los Angeles, in the county of Los Angeles and State of California, have invented a new, original, and ornamental Design for a Textile Fabric, of which the following is a specification, reference being had to the accompanying drawing, forming part thereof.

The figure of the drawing is a plan view of a textile fabric showing my new design.

The dot and dash lines on the drawing outline substantially the design unit, which unit is repeated in regular succession as indicated by the extensions beyond the unit boundaries.

I claim:

The ornamental design for a textile fabric, substantially as shown and described.

ANNETTE HONEYWELL.
